[57] CLAIM

The ornamental design for a combined bulb and cap for a dropper applicator, substantially as shown and described.

DESCRIPTION

FIG. 1 is a top front perspective view of a combined bulb and cap for a dropper applicator, showing my new design, the broken lines indicating a container and dropper barrel are shown for illustrative purposes only; FIG. 2 is a bottom rear perspective view thereof; FIG. 3 is a front elevational view thereof, the rear view being a mirror image thereof; FIG. 4 is a left side elevational view thereof; FIG. 5 is a right side elevational view thereof; FIG. 6 is a top plan view thereof; FIG. 7 is a bottom plan view thereof; FIG. 8 is a top front perspective view of a second embodiment of that shown in FIG. 1; FIG. 9 is a bottom rear perspective view thereof; FIG. 10 is a front elevational view thereof, the rear view being a mirror image thereof; FIG. 11 is a left side elevational view thereof; FIG. 12 is a right side elevational view thereof; FIG. 13 is a top plan view thereof; FIG. 14 is a bottom plan view thereof; FIG. 15 is a top front perspective view of a third embodiment of that shown in FIG. 1; FIG. 16 is a bottom rear perspective view thereof; FIG. 17 is a front elevational view thereof, the rear view being a mirror image thereof; FIG. 18 is a left side elevational view thereof; FIG. 19 is a right side elevational view thereof; FIG. 20 is a top plan view thereof; and FIG. 21 is a bottom plan view thereof.
